UNITED STATES PATENT OFFICE.

CHARLES L. NORTON, OF HUDSON, NEW HAMPSHIRE, ASSIGNOR TO ASBESTOS SHINGLE COMPANY, OF NASHUA, NEW HAMPSHIRE, A CORPORATION OF NEW YORK.

MACHINE FOR MAKING CONCRETE SLABS OR PLATES.

1,140,704.

Specification of Letters Patent.

Patented May 25, 1915.

Application filed July 20, 1914. Serial No. 851,858.

To all whom it may concern:

Be it known that I, CHARLES L. NORTON, a citizen of the United States, and resident of Hudson, in the county of Hillsboro and 5 State of New Hampshire, have invented new and useful Improvements in Machines for Making Concrete Slabs or Plates, of which the following is a specification.

This invention relates to the art of continuous production of concrete slabs or plates, and is an improvement upon the art as represented by United States Letters Patent No. 979,548, dated December 27, 1910.

The object of the invention is to insure a greater regularity of product than has heretofore been obtained, and to obviate the necessity of the nice adjustments of machine and materials, and the close vigilance, which the employment of the machine described in 10 the said patent entailed. That machine (and the method practised by it) was characterized chiefly by compressing a band of concrete-material in two distinct stages, first dry, and then wet, and so far as experience 15 has taught those who practise this art, this characteristic two-stage method of procedure cannot safely or practically be dispensed with, if indeed it is dispensable at all. The specific mode by which the separation of 20 the wet and dry regions of the plate making machine of the said patent was accomplished, lay in the employment of two separate and distinct belt conveyers, one of which took the dry material, and sustained it 25 during the dry-pressing, the other of which received the dry-pressed material from the first, conveyed it and sustained it while it was being first wetted and then wet-pressed, finally delivering it, severed 30 into plates. The transfer of dry material from the dry belt to the wet belt involved the rather delicate operation of shoving the dry-pressed band of material across a smooth metal bridge, placed between the 35 adjacent ends of the two belts. Under the supervision of skilled attendants this operation could be, and was, performed successfully and on a commercial scale, but any relaxation of vigilance on the part of these 40 attendants, or any change for the worse—in respect to skill and knowledge—in the attendants, rendered the machine liable to slips in between, and detracted from the uniform excellence desired in the product. 45 Specifically, therefore, the object of this in-

vention (which has been attained in commercial practice) is, to dispense with the physical separation of the two conveyers and therefore to dispense with the bridge (which occasionally, under the stress of industrial operation of the machine of the Patent No. 979,548 became truly a "bridge of sighs") while conserving the values of separation of the dry-pressing region from the wet-pressing region. In brief, this is accomplished 60 by the employment of a single endless belt conveyer, which carries the material through the dry-press rolls, to the water supply, through the wet-press rolls, delivers the product, returns, is deprived of all undesirable moisture, and again engages the continuously supplied dry material. 70

In the drawings hereto annexed, which illustrate the invention, Figure 1 is a diagrammatic side elevation of a machine embodying the invention, and Fig. 2 is a detail, showing the mechanical scraper for cleansing the conveyer and removing part of its moisture. 75

The numeral 1 represents the conveyer, which is an endless belt, preferably of canvas and rubber, A is a hopper to deliver concrete-material to the receiving end of the conveyer, 2, 2, are the dry-press rolls, 3, 3, the wet press rolls, 4 a rotating cutter frame which grooves the band of concrete-material laterally, to facilitate its subsequent separation into plates, 5 is the water-sprinkler, 6 the delivery roll, and L a rotating brush or scraper frame, armed with rubber "squeezers" and rotated so as to wipe solid and liquid materials from the conveyer 1 during its return movement toward the hopper A. 80

B is a conveyer for surplus material, which is scraped from the conveyer 1, first 95 by a right and left pitched worm 7, then by a rotary brush 8, and finally by side scrapers 9, of which there is one at each side of the conveyer 1. Plates 11 (one at each side of the conveyer 1) guide surplus material to the return-conveyer B. The conveyer B also receives the spill from the hopper A, through the chute F, and delivers all the surplus material to the chute C, which 100 passes the material to the hoist D, which in turn delivers it again, through pipe I and chute C to the top of the hopper A. Meanwhile fresh supply, delivered by another hoist (not shown) passes through pipe E to 105 hopper A. The mechanism for handling 110

the material is so arranged and the supply so regulated, that there is a continual spill from the top of the hopper A, and also from the receiving end of the conveyer 1. Since the concrete-material contains finely comminuted cement, a thick dust cloud is produced at this end of the machine, which is, in practice, provided with a housing (not shown) so as to confine the dust as securely as possible. This cement dust is, however, by no means an unmitigated nuisance, since, in the specific embodiment of the invention here shown, it performs a distinctly useful and pertinent function.

In order to restore the conveyer 1, after it has been thoroughly wetted by the drenched concrete material in the wet region in suitable condition for the dry-pressing part of the cycle, it is so manipulated and treated on its return from the delivery roll 6 to the hopper A, that practically all moisture is eliminated from it. This elimination of moisture may be accomplished in divers ways that will occur to the engineer or machine designer; the injunction to rid the conveyer of moisture will suggest heaters, fanning devices, dry-air currents, drying rolls, drying chambers, and what not, any of which will perform the prescribed function. Preferably, however, the restoration of the conveyer to proper condition for the preliminary dry-pressing of the material, is carried out in the manner here illustrated, to wit:

The rotating "squeegee" scraper L, striking the surface of the conveyer 1, beats off a large part of the adhering moisture—and incidentally any fragments of solid material that may have remained upon it, but leaves the surface still somewhat damp to the touch. In this condition the conveyer passes into the cloud of cement-dust where the

surplus material is spilled on to the conveyer B. This dust absorbs the remaining moisture on the conveyer, and produces a 45 powdery surface which is as if dusted with talc-powder and in the best possible condition for the reception and dry-pressing of the material received from the hopper A.

By the means above described, the band 50 of concrete-material carried by the conveyer 1 is subjected to no such precarious treatment as was involved by the employment of the physically separate conveyers of Patent No. 979,548 and the intervening bridge, 55 while the distinction between wet and dry regions is preserved.

What I claim, and desire to secure by Letters Patent, is:

1. In a machine of the character described, the combination of an endless belt conveyer, means to supply material to the conveyer, dry-press rolls, wetting devices, wet-press rolls, a delivery roll, and means to confine a cloud of cement-dust about the 60 conveyer, between the delivery roll and the material-supplying means.

2. In a machine of the character described, the combination of an endless belt conveyer, means to supply material to the 70 conveyer, dry-press rolls, wetting devices, wet-press rolls, a delivery roll, a mechanical device for removing moisture from the conveyer, and means to confine a cloud of cement-dust about the conveyer, between 75 the delivery roll and the material-supplying means.

Signed by me at Boston, Massachusetts, this thirteenth day of July 1914.

CHARLES L. NORTON.
